D. W. BRUNTON.
ILLUMINATED TRANSIT.
APPLICATION FILED SEPT. 15, 1917.

1,339,019.

Patented May 4, 1920.

UNITED STATES PATENT OFFICE.

DAVID W. BRUNTON, OF DENVER, COLORADO.

ILLUMINATED TRANSIT.

1,339,019.

Specification of Letters Patent.

Patented May 4, 1920.

Application filed September 15, 1917. Serial No. 191,559.

To all whom it may concern:

Be it known that I, DAVID W. BRUNTON, a citizen of the United States, residing at Denver, in the county of Denver and State 5 of Colorado, have invented a certain new and useful Improvement in Illuminated Transits, of which the following is a full, clear, and exact description.

The object of this invention is to provide 10 a transit, compass or the like with means whereby it is adapted for use either in the light or in the dark, and it has reference particularly to the pocket transit of my Patents No. 526,021, dated September 18, 15 1894, No. 1,042,079, dated October 22, 1912, No. 1,062,582, dated May 27, 1913, and No. 1,092,822, dated April 14, 1914.

The invention consists in a transit, compass or the like having a transparent cover 20 plate provided with luminous indicia rendered non-diffusive with reference to the interior of the instrument so that the instrument may be used for surveying or marching at night or in the dark, without in the 25 least impairing its usefulness in the light, as I will proceed now to explain and finally claim.

In the accompanying drawings illustrating the invention, in the several figures of 30 which like parts are similarly designated, Figure 1 is a plan view of a transit in open position, showing the application of the invention thereto. Fig. 2 is a view showing the reverse side of one of the sight arms. Fig. 3 is a view showing the reverse side 35 of the other sight arm. Fig. 4 is a view greatly enlarged, showing a fragmentary section of the transparent cover plate and one of the luminous indicia. Fig. 5 is a 40 plan view of a cover plate graduated and numbered in accordance with the requirements of the Chief of Engineers, United States Army.

The transit or compass shown is of the 45 type known as "Brunton's pocket transit", and comprises the usual casing 1 and cover 2 provided with the sighting arms 3 and 4, respectively. The casing 1 has a graduated ring 5 and combined vernier 6 and 50 level 7, and an indicating or magnetic needle 8, and all of these parts are mounted beneath a transparent cover plate 9, preferably of glass, held in place by a ring 10. On the under side of the plate 9 is arranged 55 a circular series of indicia 11 of luminous paint or the like, the paint preferably made

luminous by a small content of radium, and these indicia are provided with a backing 12 of opaque substance, such as an opaque paint, to prevent diffusion of the 60 light of the indicia to the interior of the casing and its contained elements so that there will be no confusion of the graduations on and below the cover plate 9 when the instrument is used in the dark. The 65 circular series of graduations 11 are spaced ten degrees apart and are numbered counter-clockwise, and like the silver or daylight circle underneath are graduated counter-clockwise from zero to three hundred 70 and sixty degrees. To avoid the employment of unnecessary figures the zero on each of the illuminated numerals is omitted, thus 3 means thirty degrees and 6 means sixty degrees. All of the indicia, including 75 the graduations for each ten degrees, are made luminous and opaquely backed as described.

As shown in Fig. 5, the luminous plate is graduated and numbered in accordance 80 with the regulations of the Chief of Engineers, United States Army, governing the graduation and numbering of surveying instruments for military uses. In accordance with these regulations, directions must 85 be given in azimuth, and this term is used to define the angular distance measured to the right of a meridian, or clockwise. In order, therefore, that readings on an instrument of the type of mine may be taken directly from the end of the needle, the graduations of a complete circle on the compass dial must be counter-clockwise. Under the old system of graduating in quadrants, it was necessary to give a direction in at least 90 three terms, as, for example, north 60 west; whereas under the present system the reading for the example above given, would be simply 60. As shown, the luminous graduations are spaced ten degrees apart, as indicated by the shorter lines, and arranged 95 in thirty degree groups, as indicated by the longer lines, and the numerals being applied to the group lines, the cipher being omitted but understood. Of course, the 100 graduations on the lower circle are also from zero to three hundred and sixty counter-clockwise, and the cardinal points omitted from the dial, thus simplifying the numbering. Of course, the graduations and 105 numbering will be varied to suit different systems and for different uses. For ex-

ample, for artillery service the instruments will be graduated in mills (6400 mills equals 60 degrees).

The needle 8 has the whole of its north end 13 made luminous, as indicated in solid black, but only a portion of its opposite end 14 is made luminous, as shown in the same manner, whereby the user will be able readily to distinguish the two ends of the 10 needle in making readings of observations in the dark.

In addition to the luminous indicia on the cover plate 9 and the luminous needle 8, the sighting arm 3 is provided on opposite sides 15 with luminous sight points 16 and 17 respectively adjacent the sight opening 15, and the sight opening 18 of sighting arm 4 is similarly provided with sight points 19 and 20.

20 The sight line 21 of mirror 22 of the cover 2 is provided with a luminous point 23.

As indicated by Fig. 1 of the drawings, the indicia on the cover plate 9 do not interfere with the observation of the vernier and 25 scales beneath the plate 9 when the instrument is used in the light; but when used in the dark, all of the light emanating from the luminous indicia is projected outwardly through the cover plate, owing to the opaque 30 backing of the indicia, leaving the interior of the casing 1 and everything below the cover plate 9, except the needle 8, in complete darkness and invisible, thus eliminating the possibility of a confusion of readings. Moreover, the indicia, including the 35 graduations are of such a size and so spaced that the aura around each one will not con-

verge with those of the ones adjacent, thus preventing the formation of a halo or confusion of illumination which would interfere 40 with easy observation of the indicia.

As already sufficiently indicated, the luminous indicia are placed on the back or inside surface of the glass cover, and they are thus arranged in order to be free from atmospheric influences, as well as protected from disfigurement or erasure by surface contact with the operator's hands and other objects, and also so that the diffusion of their light may be controlled, as already explained. 50

Various changes in details and arrangement are contemplated as within the spirit of the invention and the scope of the claims following.

What I claim is:—

1. In a transit or the like, a transparent cover plate, luminous indicia applied to the under side of said plate and a backing of non-luminous material applied to the indicia to prevent the diffusion of the light of 60 the indicia to the subjacent parts of the instrument.

2. In a transit or the like, a transparent cover plate, luminous indicia applied to the under side of said plate, and an opaque substance applied to and covering the under side of said indicia. 65

In testimony whereof I have hereunto set my hand this 14th day of September, A. D. 1917.

DAVID W. BRUNTON.
